UNITED STATES PATENT OFFICE.

CHRISTOPHER FASSNACHT, OF SOUTH BEND, INDIANA.

BOX.

No. 922,685.

Specification of Letters Patent.

Patented May 26, 1908.

Application filed March 16, 1908. Serial No. 421,549.

To all whom it may concern:

Be it known that I, CHRISTOPHER FASSNACHT, a citizen of the United States, residing at South Bend, in the county of St. Joseph and State of Indiana, have invented certain new and useful Improvements in Boxes, of which the following is a specification.

This invention relates to packing or shipping boxes.

10 One object of the invention is to provide a box for shipping or packing purposes which is so constructed that it may be readily knocked down and quickly assembled, whereby it may be shipped either in its set-up or knocked down condition.

Another object of the invention is to provide a box of the character stated embodying such characteristics that it may consist of but few parts which may be readily assembled and firmly bound together against accidental separation of one part with relation to another.

A still further object of the invention is to provide for a double strength at the points 25 of connections of the sides to the ends of the box and in such a manner as to obviate the formation of sharp points or projections liable to injure a person in handling the box.

30 With the above and other objects in view, the present invention consists in the combination and arrangement of parts herein-after more fully described, illustrated in the accompanying drawings, and particularly 35 pointed out in the appended claims, it being understood that changes may be made in the form, proportion, size and minor details without departing from the spirit or sacrificing any of the advantages of the invention.

40 In the drawings:—Figure 1 is a perspective view of a box illustrating my invention. Fig. 2 is a detail perspective view of one side of the box. Fig. 3 is a longitudinal sectional view. Fig. 4 is a detail view of one of the binding 45 wires.

Referring now more particularly to the accompanying drawings, the reference characters 1 and 2 indicate the ends of the box, and each side of the box may consist of several 50 strips 3, 4, and 5 of veneer, or if preferred, each side may be formed of a single piece of material. If each side is composed of three pieces of material, the three pieces will be firmly secured together by means of a series 55 of binding wires, 6, stapled to the strips 3, 4,

and 5 at each end thereof and also intermediate the ends, as shown. One end of each binding wire 6 is bent back upon itself to form an eye 7 and twisted as indicated at 8, while the opposite end of each binding wire 60 is bent back upon itself to form an elongated tongue 9 and twisted as indicated at 10. By forming the eye 7 at one end and the tongue 9 at the opposite end of the binding wire, there are no sharp projections liable to injure a 65 person in the handling of the box.

In setting up my improved box, each side may be nailed to the corresponding edge of the ends 1 and 2, and the tongue 9 of the corresponding binding wire 6 passed through 70 the eye 7 of the adjacent alining binding wire 6, as clearly shown in Fig. 1.

From the foregoing, it will be seen that an exceedingly simple, inexpensive, durable and efficient box is provided and that double 75 strength is obtained at the points of connection of one side with relation to another.

What is claimed is:

1. A box of the class described comprising ends and sides, each side having a series of 80 eyes projecting from one edge thereof, and a series of tongues projecting from the opposite edge, each tongue being disposed directly opposite to an eye and connected thereto by a single wire integral with both 85 eye and tongue, the tongues of one side entering the eyes of the adjacent side and bent back upon themselves to lock the sides together.

2. A box of the character described comprising ends and sides, and a binding wire secured to each side, each binding wire being bent back upon itself at one end with its extremity twisted around the body of the wire to form an eye and bent upon itself at its opposite end parallel to and contiguous with the body portion with its extremity at said opposite end twisted around the body of the wire to form a tongue, the tongue of one binding wire being adapted to pass through 95 the eye of the binding wire upon the adjacent side of the box and bent back upon the twisted portion of the body of the wire from which the tongues are formed.

3. A box of the class described comprising 105 rectangular end pieces, side pieces secured to and connecting the end pieces, each side piece composed of a plurality of strips connected together by a series of single strand wires, each wire being bent upon itself at one 110

end to form an eye with its extremity twisted around the body portion and at its other end being bent upon itself parallel to the body portion with its extremity twisted around the body portion to form a tongue, the eyes of each series being disposed along one edge of each side and the tongues being disposed along the opposite edge, and the tongues of

one side entering the eyes of the adjacent side to secure the sides together.

In testimony whereof I affix my signature, in presence of two witnesses.

CHRISTOPHER FASSNACHT.
